ACTUATING MECHANISM FOR WORK SUPPORTS

Filed March 11, 1919 . 2 Sheets-Sheet 2

Fig. 3.

INVENTOR:

UNITED STATES PATENT OFFICE.

JOHN M. BENJAMIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

ACTUATING MECHANISM FOR WORK SUPPORTS.

Application filed March 11, 1919. Serial No. 281,939.

To all whom it may concern:

Be it known that I, JOHN M. BENJAMIN, a citizen of the United States, residing at Beverly, in the county of Essex and State of Massachusetts, have invented certain Improvements in Actuating Mechanism for Work Supports, of which the following description, in connection with the accompanying drawings, is a specification, like reference characters on the drawings indicating like parts in the several figures.

This invention relates to actuating mechanism for work-supports, and particularly to those associated with machines for attaching loaded heels, or those in which the heels operated on carry nails for affixing them to shoes. In heel-attaching machines of the type illustrated in United States Letters Patent No. 1,157,688, Glidden, October 26, 1915, in which heels and top-lifts are secured to shoes by nails supplied to the machine, it is customary to shift the heel and top-lift support from its top-lift-attaching to its heel-attaching position under the influence of the nail-transferring mechanism when this is moved from the distributing mechanism to deliver its load of nails to the nail-block or templet of the machine. With loaded heels, however, the nail-transferring mechanism is not used, and the body portion of the heel is usually placed directly upon the nail-block.

Under such conditions as are above outlined, an object of the present invention is to furnish means for actuating a support at the correct time in the cycle of operations. In the attainment of this object, I provide, in a machine having a plurality of movable work-supports, means for moving one of said supports from another in one direction only, movement in another direction being preferably under the influence of actuating means. In the illustrated embodiment of the invention, connections between the shoe-support, or jack-post, and the heel-portion-support, or swing-plate, cause them to move together, the preferred relation being, that when the jack is carried to its non-operating position to enable a fresh piece of work to be supplied, the swing-plate is shifted from its top-lift-attaching to its non-attaching position, the latter being that in which the

body of the heel is secured to the shoe. The opposite movement of the support, as that of the swing-plate in which it co-operates with the jack, is effected by the previously mentioned actuating means and under the control of the associated support, or jack. The moving means and actuating means preferably have elements in common. To permit a variation in position of a support without effect upon the companion support which receives movement from it, the moving means, or connections between the supports, have provision for allowing such variation. When the invention is embodied in a heel-attaching machine, the horizontal adjustment of the jack, to correctly locate the work with respect to the nail-block, may be provided for by a shifting pivot in the connections to the swing-plate; while the vertical travel or work-positioning movement of the jack is caused to be without ill effect upon the mechanism of this invention by the presence of a connecting element long in comparison with the travel. To insure the correct relation of the support and the associated elements, I furnish means to vary the extent of its travel, as by including an adjustable element in the connections through which the movement is effected.

In the accompanying drawings, Fig. 1 is a side elevation of a portion of the machine including one embodiment of my invention;

Fig. 2 is an enlarged horizontal section on the line 2—2 of Fig. 1; and

Fig. 3 is an enlarged perspective view of the elements more closely concerned with this invention.

In its general characteristics, the machine herein illustrated is similar to that disclosed in the previously mentioned patent, the nail-driving mechanism not appearing. As to the elements more directly co-operating with the work, a jack-post 10 for supporting a lasted shoe, indicated at S, is pivoted at 12, for movement between operating and non-operating positions, upon a slide 14 adjustably mounted for movement from front to rear of the machine in a head 16. This head is carried by a vertical rod 18, arranged for reciprocation in a bearing in the frame 20 and articulated at its upper extremity to a

top-lever 22 fulcrumed upon the frame. The top-lever and connected jack are oscillated by a rod 24 joined to the power-shaft of the machine, this latter element not being shown.

- 5 Pivoted as usual upon the cross-head 26, above the nail-block, or templet 28, is a swing-plate 30 for supporting a heel-portion, in the present instance a top-lift, which is to be attached to a jacked shoe, this heel-portion of the work being carried by a suitable holder 34. The swing-plate is connected by a rod 36 to a rock-shaft 38, journaled vertically at the rear of the frame and having connected to it an actuating device, as 10 a helical spring 40, which is shown as encircling the rock-shaft, and so connected as to exert its tension to move the swing-plate from a position clear of the nail-block, when the heel is carried upon said block, to that 15 20 in which the top-lift is located below the shoe. The swing-plate is temporarily retained in the first, or inactive, position by a latch 42 mounted on an arm 43, fixed to the rock-shaft and arranged to engage an 25 element carried by the frame. Cooperating with this latch is a tripping device 44, mounted upon a bracket 46 secured upon the jack-actuating rod 24. When the rod 24 moves upwardly at the beginning of the 30 heel-attaching operation, the tripping device passes idly by the latch, but, on the reverse movement, the device 44 frees the latch and allows the swing-plate to travel to its top-lift-attaching position. 35 To move the swing-plate in the opposite direction, or from the top-lift-attaching position to one clear of the nail-block, when the spring 40 is tensioned and the swing-plate is latched, the following moving or 40 connecting means is provided. Fulcrumed at a convenient point upon the head 16 adjacent to the pivot pin 12 of the jack-post, is a lever 48, preferably in the form of a bell-crank having a rearwardly extending arm 50 and an upwardly extending arm 52. The arm 50 is pivoted at 54 to a projection 56 from the jack-post, which projection may consist of an extension of the arm to which is connected the chain 58 of the band-clamp 45 50. The arm 52 of the lever 48 is joined by a rod 62 to a lever 64 fulcrumed at 66 upon the frame of the machine. This last-mentioned lever is forked at 68, the arms extending at opposite sides of the rod 36. Adjacent to the fork, the rod is threaded at 70, and adjustably mounted upon this threaded portion is a contact member or disk 72, the rear face of which rests against curved edges 74 of the fork. 55 After the completion of a heel-attaching operation, the swing plate is in the position illustrated in Fig. 2 of the drawings, with the top-lift holder 34 in its active relation. As the jack-post is swung out by the operator to the angle shown in Fig. 1 for the pur-

pose of removing the heeled shoe and supplying another lasted shoe for the heel-attaching operation, the projection 56 from the jack-post rocks the lever 48 upon its fulcrum, moving the rod 62 rearwardly, this in turn, 70 through the lever 64, pressing the edges 74 of the fork against the contact-disk 72. Consequently, the rod 36 travels toward the front of the machine, moving the swing-plate about its pivot in an anticlockwise direction as viewed in Fig. 2, until the swing plate is retained by the latch 42 clear of the nail-block. As previously indicated, this relation is maintained until the heel-attaching operation is completed, when the tripping device 44 releases the latch and the swing-plate oscillates to the top-lift-attaching position under the influence of the spring 40. 75 80

To enable an adjustment of the jack-post from front to rear of the machine, or in the reverse direction, to be made without affecting the extent of movement of the swing-plate, the pivot pin 54 operates in a slot 76 extending longitudinally of the arm 50 of 85 the lever 48 and, when the jack is at its extreme of forward travel, this slot is substantially horizontal. It will be evident that the shifting of the pin in the slot will cause the swinging out of the jack-post to always move the lower extremity of the lever 48 to the same point and thus fix the position to which the swing-plate is carried by contact of the lever with the disk 72. Because the rod 62 is long as compared with the extent 90 of vertical movement of the jack-carrying slide 18, this movement has no material effect upon the angular position of the lever 64, and, therefore, the swing-plate is unaffected by this alteration in the location of 95 the jack. The extent of movement of the swing-plate under the influence of the connecting mechanism may be adjusted by changing the location of the contact-disk 72 upon the thread 70 of the rod 36, thus altering the time at which the contact surface 72 of the fork comes into effective co-operation with the disk. Or this movement of the swing-plate may be varied by changing the 100 length of the rod 62 by means of a right and left-handed nut 78 engaging corresponding threads 80 upon separated portions of the rod 62. 105 110 115

Having described my invention, what I claim as new and desire to secure by Letters Patent of the United States is:

1. A machine of the class described comprising supports for the work movable in different directions, and means arranged to move one of the supports from another support in the movement of the latter and in one direction only. 120
2. In a machine of the class described, movable work-supports, means for actuating one of the supports, means for control-

ling its movement in the movement of another support, and means arranged to move one of the supports as a result of the movement of another support.

5. 3. In a machine of the class described, movable work-supports, means for actuating one of the supports, means for controlling its movement in the movement of another support, and means arranged to move the actuated support as a result of the movement of the controlling support.

4. In a machine of the class described, movable work-supports, means for actuating one of the supports, means for controlling its movement in the movement of another support, and means having elements in common with the actuating means arranged to move the actuated support as a result of the movement of the controlling support.

5. A machine of the class described comprising co-operating shoe- and top-lift-supports, said supports being movable between work-receiving and operating positions, connections between the supports arranged to cause the movement of the shoe-support from the operating to the work-receiving position to correspondingly move the top-lift support, and means independent of the shoe-support for moving the top-lift support from the work-receiving to the operating position.

6. In a heel-attaching machine, a movable shoe-support, a heel-portion holder movable into two extreme positions, actuating means for moving the holder from one extreme position to the other, and means arranged to cause the movement of the shoe-support to move the holder from such extreme position to the opposite extreme.

7. In a heel-attaching machine, a movable shoe-support, a heel-portion-holder movable into attaching and non-attaching positions, actuating means for moving the holder to the attaching position, and means arranged to cause the movement of the shoe-support to move the holder to the non-attaching position, the movement imparted by the support to the holder being in one direction only.

8. In a heel-attaching machine, a nail-block, a shoe-support movable toward and from the nail-block between operating and non-operating positions, a top-lift-holder movable into and out of co-operation with the nail-block and shoe-support, and means arranged to cause the movement of the shoe-support from its operating to its non-operating position to move the holder from co-operation with the nail-block and shoe-support.

9. In a machine of the class described, a shoe-support and a heel-portion-support, said supports being movable, means for moving the heel-portion-support, means ar-

ranged to control said movement in the movement of the shoe-support, and connections between the supports to impart the movement of the shoe-support to the heel-portion-support.

10. In a machine of the class described, a shoe-support and a heel-portion-support, said supports being movable, power means for moving the heel-portion-support, and connections between said moving means and shoe-support to impart movement to the heel-portion-support.

11. In a machine of the class described, a shoe-support and a heel-portion-support, said supports being movable, power means for moving the heel-portion-support, and connections between said moving means and the shoe-support to actuate the heel-portion-support oppositely to the movement imparted by said moving means.

12. A machine of the class described comprising movable supports for the work, means to permit a variation in position of one of the supports, and means arranged to move another of the supports from the positioned support, said moving means having provision for allowing the previously mentioned variation while the position of the associated support is maintained constant.

13. A machine of the class described comprising a shoe-support and a heel-portion-support, said supports being movable, means to permit a variation in position of one of the supports, and connections between the supports to cause them to move together and including arms pivoted to each other, the pivotal connection being arranged to shift along an arm and allowing one of the supports to remain unaffected during the variation of the other.

14. A machine of the class described comprising a shoe-support and a heel-portion-support, said supports being movable, means to permit a variation in position of one of the supports, and connections between the supports to cause them to move together, said connections including an element pivoted at its ends to the associated connecting elements and being relatively long as compared with the variation.

15. A machine of the class described comprising movable supports for the work, and means arranged to move one of the supports from another support in the movement of the latter, there being provision in the moving means for varying the extent to which the support is moved.

16. A machine of the class described comprising a shoe-support and a heel-portion-support, said supports being movable, and connections including an adjustable element between the supports to cause them to move together.

17. In a heel-attaching machine, a jack, a nail-block fixed for co-operation with said

jack, a heel-portion-carrying swing-plate movable across the nail-block, and actuating connections between the jack and swing-plate.

5. 18. In a heel-attaching machine, an oscillatory jack having a projection therefrom, a nail-block across which the jack moves, a swing-plate pivoted adjacent to the nail-block, and connections between the jack-projection and swing-plate.

10. 19. In a heel-attaching machine, a jack-carrier, a jack movable thereon, a lever upon the carrier for engagement by the jack, a heel-portion-carrying swing-plate, and connections between the lever and swing-plate.

15. 20. In a heel-attaching machine, a frame, a jack-carrier mounted thereon, a jack movable upon the carrier, levers fulcrumed upon the frame and carrier, a swing-plate, and connections between the levers and from the levers to the jack and swing-plate.

20. 21. In a heel-attaching machine, a jack, a heel-portion-carrying swing-plate, and actuating connections between the jack and swing-plate, said connections including a slot and a pin movable in the slot.

25. 22. In a heel-attaching machine, a jack, a plate organized to position a work-portion, actuating connections between the jack and plate, and means arranged to vary the length of one of the connecting elements.

30. 23. In a heel-attaching machine, a jack, a

swing-plate, an actuator for the swing-plate, a connector between the actuator and swing-plate, and means operable by the jack arranged to engage the connector and move the swing-plate.

35. 24. In a heel-attaching machine, a jack, a swing-plate, an actuator, a connector for moving the swing-plate from the actuator in one direction, and means operable by the jack and engaging the connector to move the swing-plate in the opposite direction.

40. 25. In a heel-attaching machine, a jack, a swing-plate, an actuator for the swing-plate including an element arranged for adjustment as to its normal position, and means operable by the jack for engaging said variable element.

45. 26. In a heel-attaching machine, a jack, a swing-plate, a spring, a rod connecting the spring and swing-plate, and a lever system movable by the jack and co-operating with the rod.

50. 27. In a heel-attaching machine, a jack, a swing-plate, a spring, a rod connecting the spring and swing-plate and having a threaded portion, a contact member mounted on the threaded portion of the rod, and a lever connected to the jack and engaging the contact member.

55. In testimony whereof I have signed my name to this specification.

JOHN M. BENJAMIN.
